Specification for Design.

Patented Apr. 25, 1916.

Application filed October 16, 1915. Serial No. 56,336. Term of patent 3½ years.

To all whom it may concern:

Be it known that I, CARL ROSENBERGER, a citizen of the United States, and a resident of the city, county, and State of New York, have invented a new, original, and ornamental Design for a Bracelet-Link, of which the following is a specification, reference being had to the accompanying drawing, forming part thereof.

Figure 1 is a front elevation of a bracelet link, showing my new design; and Fig. 2 is a plan view of the same.

I claim:

The ornamental design for a bracelet link, as shown.

CARL ROSENBERGER.
